Des. 360

From & Wm H. Lewis of New York, N. Y.
Letters Patent No. 360. Dated March 25, 1851.

The Schedule referred to in these Letters Patent, and making part of the same.

To all whom these Presents may come:

Know ye,
that we, William Lewis and William H. Lewis, of the City, County &
State of New York, Manufacturers of Daguerreotype Apparatus, have in-
vented and made a new and original ornamental Design for the pedestal
and column to support or carry a table top, stool, or other useful article
for which we seek Letters Patent of the United States; and we do hereby de-
clare that the following is a full, clear and exact description of the same,
reference being had to the annexed drawing, in which Fig. 1 is a plan of
the pedestal, and Fig. 2 is a side elevation of the pedestal and column
attached.

The pedestal is formed of three or more an-
gles, with the sides between each point of support curved inwards, and
formed as a flaunch to the top of the pedestal; on the lower edge of the
sides is a bead, and the angle formed by the sides and top of the pedestal
is formed with ornamental figures; and the top of the pedestal is orna-
mented with figures in alto-relievo commencing from the centre where the
column is attached, as shown in Fig. 1 - these are a series of curves repre-
senting leaves and other plants, gradually tapering down, as they approach
the angle of the pedestal.

The column shown in Fig. 2 is a fluted shaft,
with a capital representing leaves and egg shaped bases, and the base is form-
ed to represent a bunch of leaves, surrounded by egg shaped ornaments
as shown in the drawing.

We do not mean to limit ourselves to the ma-
terial out of which this is to be formed, but we prefer a casting of iron; nei-
ther do we mean to limit ourselves to the exact size or proportions, the ornamental

portions remaining substantially as described and shewn.

What we claim as new and of our own invention, is the design and configuration shown in Fig. 1, as attached to or formed on the pedestal in alto-relievo, as described and shown, and we also claim the Design shown in Fig. 2, as forming the base of the column attached as described and shown.

In witness whereof, we have hereto set our signatures, this thirteenth day of February, one thousand, eight hundred and fifty-one.

Witnesses:

W. Gervell
Samuel W. Gervell.
